ATTORNEY.

UNITED STATES PATENT OFFICE.

ALBERT BACK, OF NEW YORK, N. Y., ASSIGNOR TO WILLIAM H. HOLEYWELL.

DESIGN FOR A RUFFLE OR RUCHING.

SPECIFICATION forming part of Design No. 21,049, dated September 22, 1891.

Application filed August 14, 1891. Serial No. 402,687. Term of patent 14 years.

To all whom it may concern:

Be it known that I, ALBERT BACK, a citizen of the United States, residing at New York, in the county and State of New York, have 5 invented and produced a new and original Design for Ruffles and Ruchings, of which the following is a specification, reference being had to the accompanying drawings, forming part thereof, in which similar letters of 10 reference indicate corresponding parts in both the figures.

Figure 1 is a side elevation of a strip of ruffling embodying the features of the design, and Fig. 2 is a section taken practically on 15 the line $x x$ of Fig. 1.

The design consists of a grouping or chain of figures A, each simulating a complete ribbed shell and having an inflated or somewhat cylindric appearance when viewed from the sides, top, or edges. All of the shell figures 20 apparently form a portion of a common base figure B.

I claim—

A design for a ruffle or ruching, substantially as shown and described.

ALBERT BACK.
